UNITED STATES PATENT OFFICE.

HENRY W. BUTTERFIELD, OF GRIGGSVILLE, ILLINOIS.

PORTABLE FENCE.

SPECIFICATION forming part of Letters Patent No. 333,279, dated December 29, 1885.

Application filed June 22, 1885. Serial No. 169,444. (No model.)

To all whom it may concern:

Be it known that I, HENRY W. BUTTERFIELD, of Griggsburg, in the county of Pike and State of Illinois, have invented a new 5 and useful Improvement in Portable Fences, of which the following is a full, clear, and exact description.

Reference is to be had to the accompanying drawings, forming a part of this specification, 10 in which similar letters of reference indicate corresponding parts in all the figures.

Figure 1 is a plan view of a portion of my improved fence. Fig. 2 is a side elevation of the same. Fig. 3 is a sectional end elevation 15 of the same, taken through the line xx , Fig. 2. Fig. 4 is a perspective view of one of the sills. Fig. 5 is a perspective view of one of the sills, showing a modified form.

The object of this invention is to provide 20 fences constructed in such a manner that they can be readily and quickly set up, taken down, and moved from place to place, and which shall be simple in construction, strong and durable in use, and inexpensive in manufacture.

The invention consists in the combination, 25 with the overlapped ends of the panels, and with the recessed sills supporting the panels, of binding brace-wires, as will be hereinafter 30 fully described.

The panels are formed of horizontal boards A, connected at their end by cross-bars B, which are preferably attached to the opposite sides of the boards A, as shown in Figs. 35 1 and 2. When the panels are long, they may be strengthened by cross-bars B', attached to their centers.

The panels A B can be made wholly of 40 boards, or of boards and a top wire, as shown in the drawings, or of boards and intermediate wires, as may be desired, or as the scarcity 45 of lumber may require.

In setting up the fence the adjacent ends 45 of the panels A B are overlapped, and are arranged with the inner edges of the end cross-bars resting against each other, as shown in Figs. 1 and 2, to prevent the said panels from being drawn apart longitudinally. The overlapped ends of the panels A B are placed 50 upon sills C, and rest in recesses D, formed in the centers of the upper sides of the said sills, which recesses are made of such a length 55 that the overlapped ends of the panels will fit into them snugly. The recesses D can be formed by attaching blocks E at a suitable

distance apart to the upper sides of the sills C, as shown in Figs. 1, 2, 3, and 4, and this construction I prefer, as it allows the said sills to be made of lighter lumber than would otherwise be necessary; or the said recesses 60 can be formed by removing a portion of the upper middle parts of the sills, as shown in Fig. 5.

To the sills C, at or near their ends, are secured by staples F or other suitable 65 means, the lower ends of brace-wires G, which are inclined laterally so as to pass the ends of the adjacent panels, and are secured at their upper ends, by staples H or other suitable means, to the top board of the other 70 panels, as shown in Figs. 1 and 2. With this construction the overlapped ends of the panels will be held firmly against each other in an erect position and in place upon the sills C. With this construction, also, by detaching 75 one end of each of the brace-wires G, the panels will be disconnected, and can be readily taken to another place and again set up, or can be compactly stored, ready for future use.

I am aware that the overlapped ends of adjacent panels have been secured together by a wire wrapped around the uprights of the panels and having its ends secured to sills, which are recessed to receive the said 85 panels; and I am also aware that the overlapped ends of the panels have been secured together and braced by braces which have their lower ends secured to the sill and their upper ends passed through openings in the 90 contiguous uprights of the panels, and I therefore do not claim such inventions.

Having thus fully described my invention, I claim as new and desire to secure by Letters Patent—

An improved fence, consisting of the sills C, having the recess D, the panels A B, having their adjacent ends overlapping with the inner edges of the cross-bars B, resting 100 against each other, and the brace-wires G, having their lower ends secured to the sills and their upper ends attached to the top boards of the panels, the said braces being inclined laterally and crossing the ends of the adjacent panels, substantially as shown and 105 described.

HENRY W. BUTTERFIELD.
